GOTTLIEB RENATUS MAGNEY, OF MINNEAPOLIS, MINNESOTA

HUMIDIFIER WITH SERIES OF DIMINISHING CONES

Application filed December 21, 1931. Serial No. 582,359.

This invention relates to a humidifying device. Such devices are now being increasingly used and proper humidification in living rooms is being emphasized by architects, 5 ventilating engineers, and physicians. It is desirable in a humidifying device, to have a humidifying unit which will give the necessary evaporation, which will be simple and compact and capable of being easily 10 installed in the desired place, such as the furnace, air duct, or room.

It is an object of this invention, therefore, to provide a humidifying device which can be easily and conveniently installed in a furnace or other form of air treating apparatus, 15 and which is in the form of a simple, comparatively small, compact and easily assembled unit.

It is a further object of the invention to 20 provide a humidifying device formed as a simple assembly or unit, which comprises a series of annular members preferably made of metal, said unit also having spaced liquid receiving surfaces converging toward one 25 end of the device, together with means for spraying liquid in finely divided form longitudinally of said unit.

It is another object of the invention to 30 provide a humidifying device comprising a compact assembly or unit having a series of spaced truncated cone members formed of sheet material, said members being assembled about a common axis in spaced relation, and decreasing in size toward one end of 35 said unit, together with means for directing a spray of finely divided liquid longitudinally of said unit, preferably in the line of said axis.

It is more specifically an object of the 40 invention to provide a humidifying device in the form of a simple, compact unit having a cup-like member at one end with a drain opening therethrough, a series of spaced annular members in the general form of truncated cones made of sheet metal, and spaced

along a common axis, said members increasing in size from said cup-like member to the other end of said unit, and an end member preferably of conical shape at said other end, 50 said end member carrying a nozzle adapted to spray finely divided liquid longitudinally of said unit towards said cup-like member.

The invention of this application is a further development and improvement upon the device shown in applicant's copending 55 application S. N. 509,359, filed January 17, 1931.

These and other objects and advantages of the invention will be fully set forth in the following description made in connection with the accompanying drawings, in which like reference characters refer to similar parts through the several views, and in which,

Fig. 1 is a view in vertical section of the 65 device, taken on line 1-1 of Fig. 3 as indicated by the arrows, some parts being shown in side elevation;

Fig. 2 is a horizontal section taken on line 70 2-2 of Fig. 1, as indicated by the arrows;

Fig. 3 is a horizontal section taken on line 75 3-3 of Fig. 1, as indicated by the arrows, some parts being broken away;

Fig. 4 is a central vertical section through 80 a furnace showing the device applied thereto;

Fig. 5 is a partial view in front elevation of said furnace;

Fig. 6 is a central vertical section through 85 an air treating apparatus showing the device applied thereto; and

Fig. 7 is a view partly in plan and partly in horizontal section of the device shown in Fig. 6.

Referring to the drawings, a humidifying device is illustrated shown as a unit having an end member 10. While this member might be varied in shape, in the embodiment of the invention illustrated it is shown as substantially conical in shape having a cen- 90

tral hub 10a at its apex which is bored to receive a nozzle 11 secured in said hub by the nut 12, and by means of which it is also connected to a liquid supply pipe 13 which will extend to a suitable source of water, either heated or at ordinary temperatures. Nozzle 11 has a discharge portion 11a which is constructed and arranged to project liquid in very finely divided condition. Member 10 adjacent the end opposite hub 10a has a projecting disk-like flange 10b provided with circumferentially spaced holes 10c adapted to receive attaching bolts to secure the humidifying unit in place. Said member 10 has at its inner side a depending comparatively sharp-edged lip 10d adapted to form a drip edge. An annular member 14 made of thin sheet material is disposed adjacent member 10 and has a projecting rim or flange 14a disposed in one plane, which flange is provided with a plurality of circumferentially spaced holes through which pass headed bolts 15. These bolts pass through spacing sleeves 16 engaging the upper sides of the disk portions 14a and a lower flat surface on member 10 between the drip edge 10d and the flange 10b. Member 14 has its outer edge turned upward slightly at a right angle a short distance outward from sleeve 16. A portion of member 14 within the flange 14a is of frusto-conical shape and has its small end directed downwardly. A plurality of annular members 17 of sheet material are provided, which members are of frusto-conical shape having their smaller ends directed downwardly, and said members decrease successively in diameter away from the member 14. Said members are connected together and the upper one thereof is connected to member 14 by headed rivets 18 spaced circumferentially thereabout, said rivets passing through spacing sleeves 19 disposed between said members 17 and between the upper one thereof and member 14, which sleeves abut the conical surface of said members and extend substantially at right angles to said conical surfaces. A cup-like member 20 is secured to the lower one of members 17 also by the rivets 18 and the spacing sleeves 19, said member 20 being substantially of conical shape and having a small opening 20a at its lower end surrounded by a short cylindrical portion. A clip or supporting bracket 21 is formed from a strip of material, the ends of which are disposed along the bottom of member 20 at opposite sides thereof and are secured to said member by the rivets 22. The bight portion of member 21 surrounds and supports a T member 23 having a vertical opening disposed coaxially with opening 20a. A short pipe section 24 extends from one end of T member 23 and another pipe section 25 is secured to the other end of T member 23. Member 25 has

threaded thereon at its other end another T member 26 similar to T member 23 and member 26 has its stem opening turned downwardly, the same having secured thereto in a drain pipe 27. A rod 28 is provided, substantially of the diameter of the bore of pipes 24 and 25 and T member 23 which is adapted to constitute a clean-out instrument, the same being bent at its end to form a ring handle 28a.

In Figs. 4 and 5 a furnace is shown comprising an outer casing 30, an inner casing 31 in which is disposed the fire pot and which communicates with a casing 31a through which the products of combustion pass to a smoke pipe 33. While the invention is applicable to any kind of furnace, the particular furnace shown is of the hot-air type, and has hot-air conduits 32 leading from the upper chamber 30a thereof. Casing 30 has a top 30b which is provided with an opening through which projects the unit shown in Fig. 1, the same having its flange 10b resting on the top of the furnace top 30b and secured thereto by screws or bolts passing through the holes 10c. The portion of the humidifying unit below flange 10b projects through the top of the furnace into chamber 30a as clearly shown, and the drain pipe 25 extends through the casing 30 of the furnace, the T member 26 being disposed without said member so that drain pipe 27 extends downward at the outer side of the furnace. It will be noted that drain pipe 25 as shown in Figs. 1 and 6 has a decided inclination downwardly. Liquid is supplied to the nozzle 11 of the humidifying unit by a pipe 34 which may be controlled by an electrically controlled valve 35. Valve 35 is controlled by a thermostat 36 shown as projecting through casing 30 and secured therein and projecting into chamber 30a. Valve 35 is shown as connected to thermostat 36 by wires or conductors 37. Valve 35 can also be controlled by a thermostat or humidistat in the rooms to be humidified or heated, or controlled to operate synchronously with an oil or gas burner. The water before passing through valve 35 preferably passes through a strainer 34a also disposed in the supply line 34.

In Figs. 6 and 7 an air conditioning apparatus in the form known as the Plenum system is shown. This apparatus comprises a casing 38 being rectangular in form at one end and having an outlet conduit 39 leading to a fan casing 40. Said casing has a contracted inlet 38a and has disposed therein a series of radiators 41. The humidifying unit shown in Fig. 1 is illustrated as supported by casing 38 and depending therefrom. For this purpose casing 38 is provided with an opening in its top between outlet 39 and the radiators 41 and flange 10b of member 10 rests on top of casing 38 and

is secured thereto by screws passing through the holes 10c. The portion of the unit below flange 10b depends into the casing 38. Water is supplied to the humidifying unit 5 and the nozzle 11 thereof by a pipe 42 controlled by an electrically operated valve 43, a strainer 44 also being disposed in the pipe 42 which pipe is shown as passing through one of the coils of one of the radiators 41. 10 Valve 43 is shown as connected by the wires 45 to a thermostat 46 disposed in the casing 38 and projecting through the wall thereof. The member 20 of the unit drains into the T 26 as previously described, from which a 15 pipe 25a extends through the front of casing 38 where it is connected to a T 26a to which a downwardly extending drain pipe 27a is connected.

In operation, when the device is used in a 20 furnace as shown in Figs. 5 and 6, water will be supplied through pipe 34 controlled by valve 35. The water will be carefully strained of all sediment or solid matter in member 34a. Valve 35 will be regulated by 25 thermostat 36 or it may be regulated to operate synchronously with an oil or gas burner. As stated, valve 35 will also probably be under the control of a humidistat in the rooms to be heated. If moisture is desired 30 in said rooms and the temperature in chamber 30a is sufficient, valve 35 will open so that fluid will be delivered under pressure to nozzle 11 and will be projected in fine mist or spray longitudinally of the unit in the 35 general direction of the axis of members 10, 17 and 20. The spray diverges from nozzle 11 and as it moves lengthwise of the unit it will impinge somewhat on member 14 and the impingement on the members 17 will 40 increase as the spray passes lengthwise of the unit, owing to the converging arrangement of the conical surfaces of members 17. The hot air passing through chamber 30a will pass through the openings between 45 members 10, 14, 17 and 20 and some of the moisture will be carried by this air to the outer side of the unit and will be evaporated by and carried along with the air through the conduits 32 and supplied to the 50 rooms. The members 14, 17 and 20 will be heated substantially to the temperature in the chamber 30a and as the mist strikes these plates, there will be a considerable degree of evaporation of the moisture and this 55 evaporated moisture will also be taken up by the air and will pass with the air through the conduits 32. Should any of the moisture impinging on the members 17 accumulate 60 thereon it will drain downwardly and inwardly onto the next members below and if any moisture collects in member 20, it will drain out through opening 20a to the pipe 25 and thence through drain pipe 27. The member 28 is provided so that 65 pipes 25, 24 and the T 23 can be readily

cleaned if necessary. It will be seen that by having the members 17 successively decreasing in diameter, that a good impingement of fine mist will be had on the surfaces of the unit and good evaporation obtained, and 70 the air passing therearound and therethrough will also evaporate moisture, all of which is carried with the air to the desired place.

In the modification shown in Figs. 6 and 7, the action of the unit will be substantially 75 the same and the air passed through the apparatus will largely pass through the unit and carry the moisture therefrom to the rooms to be heated. In said apparatus the air before taking up the moisture will pass 80 through the radiator 41 and will be heated so as to readily take up moisture. The valve 43 in the showing in Figs. 6 and 7 is controlled by thermostat 46 as well as by a 85 humidistat in the rooms to be treated, so that the water will not be turned on if the temperature in casing 38 is not sufficient to properly evaporate it. The water supplied to the unit in Figs. 6 and 7 will be filtered 90 or strained in member 44. In all operations of the unit any moisture collecting in member 10 will drip from edge 10d.

From the above description it is seen that applicant has provided a simple, very compact and highly efficient humidifying unit. The same takes up comparatively little space and it is simply made and very easily assembled. The members 14, 17 and 20 as well as the spacers 19 will preferably be made 95 of copper or other non-rustable metal. Member 10 preferably will be made as a casting. The device is easily installed in a furnace or air treating apparatus as shown and can be placed in any air duct, or if 100 desired, in a room to be humidified where it can be used in connection with a radiator. The device has been amply demonstrated in 105 actual practice and found to be very successful. A large proportion of the water delivered by nozzle 11 is evaporated so that 110 an ample supply of humidified air is assured.

It will, of course, be understood that various changes may be made in the form, details, arrangement and proportions of the parts, without departing from the scope of applicant's invention, which generally stated, consists of a device capable of carrying out the objects above set forth, in the parts and combinations of parts disclosed 115 and defined in the appended claims.

What is claimed is:—

1. A humidifier structure comprising a 120 unit having in combination, a plurality of spaced members having comparatively large openings therethrough and having liquid receiving surfaces extending about said openings, said members successively decreasing in transverse dimension across said openings toward one end of said unit, means for hold- 125 130

ing said members in spaced relation with said openings in alinement, and means for directing a finely divided mist or spray longitudinally of said unit through said 5 openings.

2. A humidifier structure comprising a unit having in combination, a plurality of spaced annular members having liquid receiving surfaces, said members being disposed substantially about a common axis and successively decreasing in diameter toward one end of said unit, means for holding said members rigidly in spaced relation, and means at one end of said unit for directing a finely divided spray or mist longitudinally of said unit substantially in the direction of said axis.

3. The structure set forth in claim 2, said members having liquid receiving surfaces extending toward one end of said unit and inwardly thereof.

4. A humidifier structure comprising a unit having in combination, a plurality of spaced frusto-conical members of sheet material disposed substantially about a common axis, said members increasing in diameter toward one end of said unit and having their surfaces substantially parallel, means for holding said members rigidly in spaced relation, and means for directing a finely divided mist or spray longitudinally of said unit substantially in the direction of said axis.

5. The structure set forth in claim 4, and a conical cup-like member secured to the annular member of smallest diameter at one end of said unit and having a small drain opening leading from its central portion.

6. The structure set forth in claim 4, and at end member for said unit of conical form secured to the larger end of said unit and having its sides converging in a direction opposite to said first mentioned members, said means for directing spray being disposed centrally of said end member.

7. A humidifying structure comprising a unit having a conical member at one end, a series of frusto conical sheet metal members secured to said member and to each other, and spaced longitudinally of said unit, said latter members successively decreasing in diameter in a direction away from said end member, all of said members being disposed about a common axis, the sides of said end member diverging toward said frusto-conical members and the sides of said frusto-conical members converging toward the end of said unit opposite said end member, and a cup member at the end of said unit opposite said end member having its sides substantially parallel to the sides of said frusto-conical members and having a drain opening therethrough, and means mounted centrally of said end member for directing

a finely divided spray or mist longitudinally of said unit.

8. The structure set forth in claim 7, a drain means secured to said unit and having an opening in alinement with the drain opening of said cup-like member, adapted to receive and carry away any liquid passing therefrom.

9. A humidifier structure comprising a unit having a plurality of spaced frusto-conical members disposed about a common axis and successively decreasing in diameter toward one end of said unit, means for securing said members together in spaced relation longitudinally of said unit, an end member secured to the large end of said unit having a supporting means extending thereabout, and means secured centrally of said end member for directing a finely divided spray or mist longitudinally or said unit.

10. A humidifier structure comprising a unit having in combination, a flaring end member having a supporting flange extending thereabout at its larger end, a plurality of annular sheet metal members secured to said member and to each other and spaced longitudinally of said unit, said members having surfaces directed toward the end of said unit opposite said end member and inwardly of said unit, being disposed substantially about a common axis co-axial with said end member and successively decreasing in diameter toward said end of said unit, and means mounted centrally of said end member for directing a finely divided spray or mist longitudinally of said unit.

11. A humidifier structure comprising a unit having in combination, a conical member at one end having supporting means for said unit thereon, a conical cup-like member of much smaller diameter at the opposite end of said unit and disposed oppositely to said first mentioned means, a series of frusto-conical members disposed in spaced relation between said cup-like member and said first mentioned member and increasing progressively in diameter from said cup-like member to said first mentioned member, and having their sides substantially parallel to the sides of said cup-like member, and means for directing a fine mist or spray longitudinally of said unit towards said cup-like member.

12. A humidifier structure comprising a unit having in combination, a plurality of members having openings therethrough and liquid receiving surfaces extending about said openings, said openings decreasing in diameter successively in said members toward one end of said unit, said surfaces being inclined toward one end of said unit, and means for directing a fine mist or spray longitudinally of said unit toward the latter end of said unit.

13. A humidifier structure comprising a

unit having in combination, a plurality of members spaced longitudinally of said unit having liquid receiving surfaces extending about openings therein and inclined toward 5 one end of said unit, means holding said members in fixed relation with said openings in alinement, said surfaces extending nearer the longitudinal axis of said unit successively in said members toward said 10 end of said unit, and means for directing a fine mist or spray longitudinally of said unit toward said end of said unit.

14. A humidifier structure comprising a unit having in combination, an end member 15 adapted to support said unit, a plurality of members having liquid receiving surfaces inclined toward one end of said unit and surrounding openings in said members, said openings decreasing in diameter in said 20 members successively toward said end of said device, and a cup-like end member at said end of said device having a drain opening therethrough.

15. A humidifying structure having in 25 combination, a unit comprising an end member, means for projecting a finely divided spray or mist carried by said member, and a plurality of members having openings therein carried by said end member and extending in spaced relation therefrom, said 30 openings being alined with said means whereby said spray can be directed through said openings.

16. A humidifying structure having in 35 combination, a unit comprising an end member, means for projecting a finely divided spray or mist carried by said member, a second end member of smaller dimension having a drain opening leading therefrom, 40 and a plurality of members disposed in spaced relation between said end members, each having an opening therethrough, said openings being alined with said means whereby said spray will be directed through 45 said openings.

17. A humidifying structure having in combination, a unit comprising spaced oppositely disposed substantially conical members of different diameters, a spray means 50 carried by the member of larger diameter for directing a spray toward said other member, and a plurality of spaced members between said end members having liquid receiving surfaces embracing openings therethrough, 55 said openings being alined with said spray means whereby spray is directed therethrough.

18. The structure set forth in claim 17, said last mentioned members diminishing in 60 diameter toward said conical member of smaller diameter.

19. A humidifying structure having in combination, a unit comprising an end member having a downwardly sloping surface disposed about a substantially vertical 65

axis, means carried by said member for projecting a finely divided spray or mist downwardly, a plurality of members below said end member spaced therefrom and spaced from each other, each having a downwardly sloping surface and openings therethrough vertically alined with said means, said end member having a depending substantially sharp edge disposed above the adjacent one of said last mentioned members from which moisture may drip to said member.
